UNITED STATES PATENT OFFICE.

WILLIAM GARFIELD SHELDON, OF LONDON, ENGLAND, ASSIGNOR TO REMINGTON TYPEWRITER COMPANY, OF ILION, NEW YORK, A CORPORATION OF NEW YORK.

TYPE-WRITING MACHINE.

1,152,921.

Specification of Letters Patent. Patented Sept. 7, 1915.

Application filed April 17, 1914. Serial No. 832,458.

To all whom it may concern:

Be it known that I, WILLIAM GARFIELD SHELDON, a citizen of the United States of America, resident of London, England, have 5 invented certain new and useful Improvements in Type-Writing Machines, of which the following is a specification.

My present invention relates especially to tally strip mechanism and its general object is to provide improved mechanism of 10 the character specified.

More specifically one of the objects of my invention is to provide novel ribbon mechanism that is especially adapted for tally 15 strip work; another specific object is to provide improved tally strip feeding and controlling devices; another object is to provide improved paper severing devices; and a still further object is to provide an improved platen construction involving a plurality of platens or backings for the paper.

To the above and other ends my invention consists in the features of construction, combinations of devices and arrangements of 25 parts hereinafter described and particularly pointed out in the claims.

The preferred form of my invention is illustrated in the accompanying drawings, wherein—

30 Figure 1 is an enlarged fragmentary front elevation of my invention applied to the platen and platen carrier of a typewriting machine. Fig. 2 is a vertical sectional view taken transversely of the platen of Fig. 1. 35 Fig. 3 is a fragmentary, vertical, sectional view taken longitudinally of the platen, said figure being on a smaller scale than Figs. 1 and 2. Fig. 4 is a fragmentary vertical sectional view taken on a plane indicated by the 40 dotted line $y-y$ in Fig. 1 and looking in the direction of the arrow at said line. Fig. 5 is a fragmentary horizontal sectional view taken on a plane indicated by the dotted line $z-z$ in Fig. 1. Fig. 6 is a vertical sectional view taken longitudinally and centrally of 45 the tally strip roll holders. Fig. 7 is a fragmentary detail elevation partly in section of the paper severing devices. Fig. 8 is a fragmentary vertical sectional view taken transversely through the platen of a No. 10 Remington front-strike typewriting machine embodying my invention. Figs. 9, 10, 11 and 50 12 are detail views of parts of the ribbon mechanism. Fig. 13 is a view corresponding

to Fig. 10 but showing the modified construction.

As shown in Fig. 8, the top plate 1 of the No. 10 Remington front-strike typewriting machine is provided with upstanding lugs 2 and 3 to which are fixed oppositely grooved track-ways 4 and 5 co-operating through anti-friction balls 6 with the grooved front and rear bars numbered respectively 7 and 8 of a truck which further comprises end bars 9. Said truck shiftably supports 65 through devices including links or connections 10 a platen frame which comprises end bars 11 and connecting cross bars 12 and 13. A rotary platen 14 which has an axle 15 is mounted on the platen frame which, together with the truck, constitutes a traveling carriage. Operatively connected with the right-hand end of the platen is a line spacing ratchet wheel 16 (Fig. 1) with which co-operates a hand-controlled pawl of 70 ordinary construction (not shown). Associated with the platen 14 are paper controlling and feeding devices comprising a deflector 17 which is supported on a rock shaft 18 bearing in the end bars 11. Protruding through suitable openings in the deflector are the sections 19 and 20 respectively of the main and secondary feed or pressure rollers, the same being mounted on rods or 75 shafts 21 and 22 which are journaled at their ends on a pair of parallel curved supports 23 pivotally mounted at 24 on the horizontal arms of three-armed levers 25, said levers being mounted on a rod or shaft 26 supported on the platen frame. The downwardly 80 extending arms of the three-armed levers are connected to springs 27 which normally maintain the pressure rollers in operative engagement with the platen, and the upwardly extending arms of said levers are 85 adapted to be engaged by fingers or lugs 28 fixed to the rock shaft 18. Fixed to the left-hand end portion of said rock shaft is a release key or lever 29 (Fig. 2) and when this lever or key is pushed rearward the 90 lugs 28 act on the three-armed levers through their upstanding arms to overcome the springs 27, swinging said levers on their axes and releasing the rollers 19 and 20.

In order to provide a suitable mounting 105 for the tally strip supporting devices the right-hand end portion of the rubber sheath 30 of the platen 14 is partly cut away as

indicated at 31, forming a wide, shallow annular depression, and the remaining portion of the sheath for the greater part of the width of this depression 31 is further entirely cut away, exposing the core 32 of the platen 14 and forming a deeper and somewhat narrower depression 33 (Figs. 1, 2, 3, 5 and 8). Suitably secured to the core 32 of the platen 14 at the ends of the depression 33 are circular metal bands or track-ways 34 which provide a support for a tube or sleeve 35 which is seated in the depression 33 and engages at its end portions with said track-ways. It will be understood from what follows that when the platen is rotated, the bands 34 will rotate within the end portions of the tube 35 but that at this time and at all other times said bands support said tube. Said tube is formed at its ends with flanges 36 which provide bearings for the reduced end portions of rollers 37, the tube being cut away or slotted as indicated at 38 to receive said rollers. These rollers are arranged at intervals around the under side of the tube. At the top portion of the tube the flanges are cut away as indicated at 39 and the tube receives a curved washer plate or covering 40 which may be of the same rubber composition as the platen sheath, the edge portions of said washer plate extending laterally outward into the cut-ways 39 and its forward edge portion being somewhat thinned down or beveled. The washer plate 40 may be secured to the face of the sleeve 35 in any suitable way. Fixed to the upper face of the sleeve 35 as by riveting and projecting upward through the washer 40 are short upright posts 41, the upper end portions whereof are threaded. Received on these posts 41 is a convex plate or bar 42 formed with openings to fit over the posts. On the posts or screw pins 41 are circular metal washers 43 interposed between said plate and the rubber washer or plate 40. Sleeves 41 provided with internal threads are screwed down on the threaded posts 41 and serve to clamp the plate 42 in place. Supported on the upper ends of the sleeves is a plate or bar 45 which is secured in place by headed screws 46 which pass through openings in said plate 45 and are screwed into the upper ends of the sleeves 44. The plate 45 provides a support for the tally strip devices while the plate 42 is a support for the tally strip ribbon mechanism. Referring first to said ribbon mechanism as illustrated in Figs. 1, 2, 5 and 8 to 12, inclusive, an arm or shaft support 47, slotted to embrace the left-hand end of the plate 42 and suitably secured thereto as by riveting, extends rearward and is perforated at its rear end to provide a bearing opening. Integral with the right-hand end of said plate 42 is an upwardly and rearwardly extending ear 48 (Figs. 1 and 2) which has secured to it by a screw 49 a bearing plate 50. This bearing plate is provided with an opening in line with the opening in the arm 47 and with another bearing opening forward of the first. Said arm 47 and said bearing plate 50 provide bearings for the outer ends of the ribbon spool shafts 51 (Figs. 1, 5 and 10). These shafts are coaxial but are movable lengthwise independently of each other. The inner end portions of said shafts bear in a bracket 52 suitably secured to the plate 42. At its inner end each shaft, as best shown in Fig. 10, is rounded to provide a ball end 53 and the outer end of each shaft is provided with a finger button 54 by which the shaft may be readily manipulated. Loosely mounted on each shaft 51 is a sleeve 55 which at its inner end is provided with a small pinion 56 and at its outer end with a circular series of saw teeth or notches 57 (Figs. 10 and 11). Suitably fixed to the outer end portion of each sleeve is a small flanged ribbon spool or carrier 58, said sleeve preferably covering the teeth 57, the sleeve and spool moving as a single piece or member. As will be understood from Figs. 5 and 10 said members are confined loosely between the bracket 52 and their outer bearings so that while free to turn on or with their shafts 51 said members are restrained from participating in endwise movements of said shafts. Each shaft is provided with a pair of radial and oppositely projecting teeth 59 (Figs. 10 and 12) which are adapted to coöperate with the teeth 57 to connect the associate spool 58 with its shaft to cause the two to rotate together. When a shaft and its spool are in operative engagement the parts are in the relationship shown in Fig. 10.

It will be understood that by pulling outward on the finger button 54 the shaft may be moved endwise to disconnect the teeth 59 from the teeth 57, the teeth 59 being withdrawn outward and housed in a depression 60 formed in the bearing plate 50. A ribbon r is suitably attached at its ends to the cores of the spools 58, its course from one spool to the other being controlled by guiding devices hereinafter described. Said ribbon is adapted to coöperate with the tally strip and is short in length as compared with the main ribbon r' indicated in Fig. 2 which is controlled by the usual vibratory mechanism of the Remington machine, this main ribbon being on the frame of the machine or non-traveling part as distinguished from the ribbon r which is carried by the traveling carriage.

Devices are provided for turning the auxiliary ribbon spools 58 to feed the carriage carried ribbon r longitudinally, said devices comprising a mutilated pinion 61 provided at its rear with a series of crown gear teeth 62 which are circularly arranged and ex-

tend around about half of the circumference of said pinion, said teeth being adapted to coöperate in alternation with the pinions 56. The pinion 61 is fast on a shaft 63 which bears in a bracket 64 secured by screws 65 to the plate 42. Said plate, together with the underlying washer plate 40 may be cut out to provide space within which the pinion 61 may turn. Said pinion 10 is arranged at the rear end of the shaft 63 which is horizontally disposed and extends fore and aft of the machine. Back of the pinion the shaft terminates in a rounded or cone-like head 66 and the pinion is confined fixedly between said head and a collar 67 which is fast on the shaft 63 and bears in a depression or seat 68 in the bracket 64. The forward end of the shaft 63 is reduced and threaded and receives a pair of interlocking nuts 69 which prevent accidental withdrawal of the shaft from its bearing. A spring 70 coiled around the shaft forward of the collar 67 urges said shaft rearward and maintains the crown teeth 62 normally in position to coöperate with the pinions 56. However, when one of the spool shafts 51 is pushed inward its ball end 53 will coöperate with the conical head 66 to cam or force the shaft 63 forward against the spring 70, the gear 20 teeth 62 being thereby carried out of operative position so that they will no longer coöperate with the pinions 56 when the shaft 63 is turned. The end of the cone 66 will coöperate with a groove 53^a formed back of 25 the ball end to maintain the parts locked in the last described relationship until the shaft 51 is pulled outward, permitting the restoration of the teeth 62 to operative position. The pinion 61 is also formed with 30 a set of teeth 71 projecting forward oppositely from the teeth 62, said teeth 71 providing a complete crown gear wheel which intermeshes with a pinion 72 secured to the inner end portion of a shaft 73 which ex- 35 tends through an opening 74 formed transversely in the right-hand sleeve 44. The right-hand end portion of said shaft takes bearing in the forward opening or hole in the bearing plate 50. To give additional 40 stability to said shaft its inner end which is reduced in diameter and projects leftward beyond the pinion 72 preferably engages in an opening 64^a formed in the bracket 64. Near its outer end said shaft 73 is provided 45 with a ratchet wheel 75 with which coöperates a pawl 76 pivoted to a pin 77 extending laterally outward from a radial arm 78 pivoted loosely on the shaft 73. A collar 79 is fixed to the shaft 73 to the left of the bearing plate 50 and a washer or spacing sleeve 80 is arranged on said shaft to the right of said plate, said sleeve being confined between the arm 78 and said spacing sleeve and said arm 78 in turn being confined be- 50 tween said sleeve and the hub of the ratchet 55 wheel 75. The construction is such that endwise movement of the shaft 73 is prevented as well as displacement of the arm 78 lengthwise on said shaft. A link 81 pivoted at its forward end on the pin 77 and 60 confined loosely between the arm 78 and the pawl 76 extends rearward and downward and is pivotally connected near its rear end by a pin 82 with a crank arm 83 fixed to the rock shaft 18 near its right-hand end and 65 extending upward therefrom. A plurality of holes 84 on said crank arm and a plurality of holes 85 in said link 81, which holes are adapted for the reception of the pin 82, afford variability in the connection between the crank arm and link and consequent change in the feed movement communicated to the shaft 73 by its pawl and ratchet devices. 70

The construction is such that each time 85 the release lever 29 is operated to release the pressure rollers 19 and 20, it acts through the crank arm 83 and link 81 to automatically actuate the pawl and ratchet devices 76, 75 to turn the main ribbon driving shaft 90 73 and causes it to actuate the sub-shaft 63, thereby turning the mutilated gear 62. The teeth constituting said mutilated gear are so arranged in respect to the pinions 56 that they can only coöperate with one of said 95 pinions at a time and it will be understood that during each complete revolution of the mutilated gear 62 it will act in alternation on said pinions. For slightly less than half 100 of its travel it will intermesh with one pinion 56 to turn the associate ribbon spool and wind the ribbon thereon, the other spool being disconnected and permitting the ribbon to unwind. During a corresponding period 105 of the same revolution the gear 62 having been turned so as to automatically disconnect it from the first pinion 56 will act on the other pinion, automatically reversing the ribbon feed and winding the ribbon back on the opposite spool. This provision is 110 made for winding the auxiliary ribbon back and forth from one of its spools to the other for a comparatively short stretch or portion of its length, the ribbon feed being automatically communicated by the feed roll release 115 mechanism and the reversal of said feed being also automatically effected without attention from the operator and independently of the ribbon itself. It will be understood that the short stretch of ribbon thus used 120 will become worn in time and in order to advance the ribbon to bring a fresh portion of it into use, the operator has only to push in against one of the buttons 54, causing an axial, inward, or sliding movement of the 125 shaft 51. This has the double effect, as will be clearly understood from Fig. 10, of connecting said shaft with its spool and of disconnecting it from the driving gear 62, said driving gear being moved forward to an in- 130

effective position. It is then only necessary to turn the finger button 54 to feed the auxiliary ribbon 58 by hand to an extent sufficient to carry the used portion entirely 5 out of the printing field and to advance a fresh portion into position, such that it can be automatically fed back and forth between the spools over the printing point when the shaft 51 has been retracted or pulled outward to the normal position. In this way, 10 provision is made for thoroughly exhausting the auxiliary ribbon by employing comparatively short sections of it until these sections are successively exhausted. The 15 length of these sections is governed to some extent by the width of the tally strip to be used, in the present instance said length being about one and a half inches.

The auxiliary ribbon is intended to operate with said tally strip along the front face or printing line of the platen and as the auxiliary ribbon spools 58 are arranged over the platen it is necessary to guide the ribbon downward from said spools and then 25 transversely at right angles so that it will be parallel with and opposite to the printing line. To this end guiding devices are provided which, as appears from Figs. 1 and 2, comprise a guide bar 86 which is arranged forward of the plate 42 and is provided near its ends with ears 87 that are curled around a pivot rod 88 secured in a longitudinal opening in said plate 42. Beyond said ears the guide bar 86 has extensions which curve downward over the front face of the platen and terminate in diagonal or inwardly inclined slotted portions 89 providing turning bars. In the present instance the ribbon spools are arranged near the ends 40 of the cut-out in the platen and the ribbon is led off one of said spools and downward over the turning bar which is below the same, thence inward at right angles to its downward course and longitudinally of the 45 platen opposite the printing line thereon, thence over the other turning bar and upward to the ribbon spool which is above the same.

Preferably an auxiliary striking surface 50 or platen is provided for backing up the tally strip so that it may properly receive type impressions through the auxiliary ribbon 7. In the present instance this auxiliary platen is in the form of a thin, oblong strip 90 preferably of the same rubber composition as the sheath 30 of the main platen. This strip is provided at its ends with pinnacles 91 which bear in open slots in lugs or fingers 92 projecting upward from a bar 93 which extends lengthwise of the platen below the printing portion of the auxiliary ribbon and is provided at its ends with rearwardly turned ears 93a which are pivotally supported on pins 94 that project laterally outward from the ends of the tube 35. A

wire spring 95 secured to a lug 96 on said bar 93 extends upward and backward through an opening 97 in said tube and engages with the back of said tube and tends normally to maintain the auxiliary platen 90 70 in contact with the sleeve just below the front beveled edge of the washer plate 40 with which said platen section 90 forms a continuous surface to facilitate the smooth and even feeding of the ribbon thereover. This feeding is further facilitated by the rollers 87 carried by said sleeve. A leaf spring 98 secured to the bracket 64 by one of the screws 65 acts on the bar 86 to maintain the ribbon guide pressed down with the printing portion of the ribbon close to the platen section 90 while a detent spring 99 also secured in place by said screw co-operates with the pinion 72 to prevent accidental operation of the ribbon feeding mechanism. The mounting of the auxiliary platen enables it to be readily removed when worn and replaced by a new platen section. To do this the bar 93 is swung outward on the pivots 24 against the pressure of the spring 95 and the platen or anvil 90 is lifted out of the open slots in the fingers 92. Then a new platen strip is inserted and the spring 95 is allowed to force it rearward into engagement with the face of the tube 35 and under the edge of the plate 40 which prevents accidental detachment of said platen strip.

The ribbon mechanism may be modified in various respects. An illustration of the changes which may be made appears in Fig. 13 where an auxiliary ribbon spool 58' fixed to a sleeve 55' provided with a pinion 56' is shown supported on a shaft 51' which bears in a support 100. Said support unlike the support 60 of the first described construction has an extension 101 formed internally with an annular groove 102 and a connecting spiral groove 103. Adapted to engage with these grooves is a radial pin 104 on the shaft 51'. In the Fig. 13 construction, in order to connect the shaft 51' with its spool 58' through the teeth 59', 57', the shaft 51' is rotated by hand instead of pushed in as in the prior construction. This rotation of the shaft causes the pin 104 to co-operate with the spiral groove 103 to cam or force the shaft inward longitudinally until the pinion 56' is brought into engagement with the annular groove 102, said groove co-operating with the pin 104 to maintain the shaft locked in its inmost position indicated in Fig. 13 at which time it will be operatively connected with its spool so that subsequent rotation of said shaft will force the spool to turn with it.

The tally strip supporting and controlling devices are illustrated in Figs. 1 to 6 and 8. They are mounted on the bar 45, which bar has a rearward extension 45a at its right-hand end, which extension is at right angles to the body of the bar 45 and terminates in 130

an eye which surrounds and bears on the platen frame bar 13, thus providing an additional support for said bar 45. The extension also prevents turning movements of the sleeve 35. Said extension may be given increased rigidity by a piece 45^b suitably fixed to its under side. An angular bracket 105 is screwed or otherwise suitably secured to the left-hand end of the bar 45 and extends upward at right angles thereto, while near the right-hand end of said bar is suitably fixed an upright arm 106. Fixedly secured to the arm 106 near its top by a headed screw 107 is a hollow rod 108 terminating at its right-hand end in a circular head or flange 109 which abuts against the inner face of the arm 106. The rod 108 provides a support for a tally delivery spool comprising a hollow core or tube 110 which is closed at its left end and at its right end is provided with a circular flange 111 which may be grooved or cut out to lighten it. The core 110 fits over the supporting rod 108 and bears rotatably thereon, being held against detachment by a headed screw 112. Said screw is threaded into the outer end of the rod 108 which may be provided on its outer face with a boss which the end of the spool core is apertured to fit over and bear on, said end being loosely confined between the head of the screw 112 and the rod 108. A rod or shaft 113 having reduced end portions which bear in the bracket 105 and the arm 106 supports the tally receiving roll holder which is arranged below the delivery holder and comprises a hollow core 114 and disk-like flanges 115 and 116 which are apertured to bear rotatably on the rod 113. A wire detent spring 117, suitably secured to the outer face of the flange 115 is adapted to engage in either of two grooves 118 and 119 formed circumferentially in the rod 113, thus allowing the roll holder or spool to rotate in either of two predetermined locations lengthwise of said rod.

Fixed to the rod 113 to the right of the flange 116 is a disk 120 provided with a laterally projecting pin 121 which is adapted to engage with any one of a plurality of holes 122 formed in the spool flange 116 when the detent 117 is engaged with the groove 118. At such times the spool is connected or clutched to the rod or shaft 113 so that rotary movements communicated to said rod will be transmitted to the spool. However, by pulling the spool toward the left, the spring 117 may be disengaged from the groove 118 and caused to engage with the groove 119, this movement disengaging the pin 121 from the hole 122 and disconnecting the spool from the rod so that the spool may be rotated by hand independently of said rod. This is convenient when it is desired to unwind the written portion of the tally strip from the receiving spool or for

otherwise controlling the tally strip independently of regular line spacing, this being readily accomplished by turning the spool by one of its flanges. The tally strip, indicated by *p'*, is in the present instance a narrow work sheet which is wound in roll form on a pasteboard core *c* which is slid on the core 110 of the delivery spool and frictionally engages therewith. The free end of the tally strip is led off from the delivery roll downward over a guide bar 123 behind the undercut or recessed portion 31 of the platen and thence upward at the front side of the same over a guide bar 123^a and to the rear of the receiving roll holder or spool to which spool it is suitably secured as by a clamping bar 124 pivoted at 125 to the flange 115 and adapted to be swung on its pivot by a tail piece 126. Said bar extends from its pivot through a slot-way 127 in the flange 115 along the core 114 and is provided at intervals with pointed pins 128 which coöperate with holes 129 in the core 114 to clamp the free end of the tally strip to the receiving roll holder. In the present instance the tally strip is preferably of paper that is of an open texture or quite thin or tissue-like and is guided over or outside of the printing or horizontally disposed portion of the auxiliary ribbon *r*, the impressions whereof are consequently off-set on the back of the tally strip and are read through the same. However, if preferred, the relationship between the tally strip and its ribbon may be reversed. The main work sheet *p* is guided around the platen between the same and the main and secondary feed rollers and its right-hand marginal portion is superposed on and overlies the tally strip, so that when its right-hand marginal portion receives type impressions through the main ribbon *r*, such impressions will be duplicated on the tally strip from the auxiliary ribbon *r*, the auxiliary platen providing a backing for the types when these duplicate impressions are made on the main and tally sheets. It will be understood that when the platen is turned to advance the work sheet *p* the tally strip *p'* will not be affected.

Line spacing movements are communicated to the tally strip by pawl and ratchet devices which are controlled by the feed roll release lever 29. Said devices, as appears from Figs. 1, 2, 4 and 6, comprise a ratchet wheel 130 which is suitably fixed to the shaft 113 to the right of the disk 120, and, if preferred, may be fixed to said disk. A detent spring 131 provided with an ear 132 is secured by a screw 133 to the arm 106 and engages with the teeth of the ratchet 130 to prevent accidental turning of the tally receiving spool. Coöperative with the ratchet wheel 130 is a pawl 134 pivoted at 135 to a lever 136 which in turn is loosely 130

pivoted on the shaft 113 between the ratchet wheel 130 and the supporting arm 106. The pawl 134 carries a leaf spring 137 which cooperates with a lateral lug or abutment 138 on the lever 136, said spring tending constantly to maintain the pawl engaged with the ratchet wheel 130. The lever 136 is pivotally connected at 139 to a link 140 which at its rear end is formed with several holes 141 that are adapted to receive a pivot pin, screw or connecting device 142 that further is adapted to engage with any one of a plurality of holes 143 formed in an upright crank arm 144 secured to the rock shaft 18, said pin 142 thereby connecting said link 140 with said crank arm. The construction is such that when the lever 29 is operated to release the main and secondary feed rollers, as to facilitate the removal of the completed main sheet *p* and the insertion of a fresh main sheet, the described connections comprising the crank arm 144, link 140 and lever 136 will operate on the pawl and ratchet devices 134, 130 to turn the tally receiving spool to a predetermined extent and thereby to effect an advance movement of the tally strip. During such operation the lever 136 turns about the axis of the shaft 113 as a center, causing the pawl 134 to revolve bodily about said center. The advance of the tally strip takes place independently of both platens, the main platen not turning during such advance. It will be seen that means are provided for automatically line spacing the tally strip and feeding the inking ribbon for the tally strip simultaneously with the throwing off of the pressure rollers; that the tally strip is fed or drawn over a fixed platen in one direction while the printing portion of the inking ribbon is fed in another direction at right angles to the direction of the movement of the tally strip; and that these feeding movements are accomplished by trains of devices connected with the feed roll release lever.

In order to maintain the tally strip in a comparatively taut condition between its two roll holders, braking devices are provided which are normally ineffective but which are automatically caused to operate on the tally delivery roll holder when the tally line spacing devices are operated. Said braking devices comprise, as shown in Figs. 4, 6 and 8, a resilient metal strip or band 145 which is adapted to surround almost completely the periphery of the flange 111 of the delivery roll holder and is anchored at one end to a lug 146 projecting laterally inward from the face of the head 109. The opposite or free end of the band brake 145 is connected by a coiled draw spring 147 with an upwardly extending finger 140^a integral with the link 140. Normally the band brake tends to swing away from the flange 111 as shown in Fig. 4 but when the release lever 29 is actuated the resulting movement of the link 140 stretches the spring 147, increasing its tension sufficiently to cause it to draw the brake band into contact with the flange 111, the resulting friction being sufficient to somewhat retard unwinding movements of the delivery spool and prevent overthrow. When the link 140 returns to normal position the inherent spring of the brake band 145 will cause it to expand to the inoperative or Fig. 4 position.

Tally strip severing devices are provided which, as shown in Figs. 1, 2, 5 and 7, comprise a horizontal severing bar 148 pivoted on a headed shoulder screw 149 which screws into the plate 45 to the right of the arm 106. The pivoted bar 148 is normally maintained in a forwardly extending position by a draw spring 150 which is anchored at one end to a pin 151 on the extension 45^a and at the other end hooks into a hole in the tail 148 of the bar 148. The action of the draw spring 150 is limited by a stop pin 152 projecting laterally from the bar 148 and adapted to contact with the outer face of the arm 106. The forward or free end of the severing bar is provided with an upright finger piece 153. Said severing bar 148 is confined between the plate 45 and a bar 154 which extends along and above said plate, said bar being mounted at its right-hand end on the screw 149 and at its opposite end on a similar shoulder screw 155. The arm 106 is notched at 106^a to afford a passage for the bar 148. Coiled springs 156 confined between the heads of the screws 149 and 155 and the bar 154 tend to press said bar downward, said springs being preferably arranged in depressions in the top of said bar. The downward movement of the bar at the right is limited by the severing bar 148 and at the left by a washer 157 which surrounds the shank of the screw 155. The bar 154 is thus spring mounted and normally provides with the bar 45 a slot-way or opening 158 through which the severing bar 148 swings, the construction enabling the width of the slot-way 158 to be increased and providing that the bar or severing blade 148 shall always snugly fit the slot during the severing motion of the blade. The tally strip *p'* passes upward in front of the slot-way 158 and is pressed against the front edges or faces of the bar 154 and bar or plate 45 by the severing bar 148 when the latter is swung toward the left and rearward. The springs maintain a close fit between said bar and the slot-way 158 during this movement and the construction enables the tally strip to be cleanly severed so that the written portion may be removed from the receiving spool and the new end portion then reconnected with said spool.

Various changes besides those specified may be made without departing from my invention and parts of said invention may be employed without other parts.

5. What I claim as new and desire to secure by Letters Patent, is:—

1. In a typewriting machine, the combination of a carriage, a platen, means for feeding over the platen a ribbon carried by the carriage, and automatically operated ribbon reversing means carried by the carriage and operating independently of the carriage carried ribbon itself.

2. In a typewriting machine, the combination of a carriage, two platens, means for guiding separate work sheets over said platens, separately controlled ribbons one for each work sheet, one of said ribbons being controlled from the frame of the machine and the second ribbon from said carriage, and means carried by the carriage for automatically reversing the direction of feed of said second ribbon.

3. In a typewriting machine, the combination of a carriage, means on said carriage for controlling a main work sheet, tally strip devices on said carriage, a carriage-carried ribbon coöoperative only with the tally strip, means for automatically reversing the feed of said carriage carried ribbon, and a ribbon supported independently of the carriage and coöperating only with said main work sheet, the main and tally sheets being arranged in superposed relationship and interposed between said ribbons.

4. In a typewriting machine, the combination of a carriage, a platen, a releasable pressure roller coöoperative with the platen to feed a work sheet, a carriage-carried ribbon, means including pawl and ratchet devices for feeding the ribbon when the pressure roller is released, and means including other pawl and ratchet devices for simultaneously feeding a second work sheet when said pressure roller is released.

5. In a typewriting machine, the combination of a carriage, a platen, a pressure roller, a releasable rock shaft operative thereon, carriage-carried ribbon mechanism including pawl and ratchet feeding devices operative from a crank arm on said rock shaft, a tally receiving spool, and means for turning said spool to feed the tally strip, said tally feeding means including other pawl and ratchet devices operative from a second crank arm on said rock shaft.

6. In ribbon mechanism for typewriting machines, the combination of a pair of ribbon spools, pinions rigid with said spools, separate shafts on which said spools with their pinions are loosely mounted, a mutilated gear coöoperative in alternation with said pinions to feed the ribbon back and forth between said spools, means for driving said mutilated gear, and devices opera-

tive by each of said shafts for throwing said gear out of operation.

7. In ribbon mechanism for typewriting machines, the combination of a pair of ribbon spools, and intermeshing gear devices 70 for driving said spools comprising a mutilated driving gear which during each of its rotations operates in alternation to drive said spools to feed the ribbon back and forth between them.

8. In ribbon mechanism for typewriting machines, the combination of a pair of ribbon spools, shafts on which said spools are loosely mounted, intermeshing gear devices for driving said spools comprising a 80 mutilated driving gear which during each of its rotations operates in alternation to drive said spools to feed the ribbon back and forth between them, and means operative by each of said shafts for throwing 85 said mutilated gear out of operation.

9. In ribbon mechanism for typewriting machines, the combination of a pair of ribbon spools, pinions rigid with said spools, separate shafts on which said spools with their pinions are loosely mounted, a mutilated gear coöoperative in alternation with said pinions to feed the ribbon back and forth between said spools, means for driving said mutilated gear, devices operative 90 by each of said shafts for throwing said gear out of operation, and sets of connecting devices for causing said spools to turn with their shafts.

10. In ribbon mechanism for typewriting machines, the combination of a pair of ribbon spools, pinions rigid with said spools, separate shafts on which said spools with their pinions are loosely mounted, a mutilated gear coöoperative in alternation with said pinions to feed the ribbon back and forth between said spools, means for driving said mutilated gear, and means operative 105 by each shaft for connecting it with its associate spool and for throwing said mutilated gear out of operation.

11. In ribbon mechanism for typewriting machines, the combination of a pair of ribbon spools carrying pinions, separate shafts on which said spools are loosely mounted, said shafts being capable of independent endwise movement and being provided each with a cam device, a spring mounted mutilated gear coöoperative with said pinions, each of said cam devices being adapted to throw said gear out of operative position, and toothed devices adapted when one of said cam devices is in operation to connect the associate spool with its shaft so that said spool will turn when said shaft is turned.

12. In ribbon mechanism for typewriting machines, the combination of a pair of ribbon spools carrying pinions, separate shafts on which said spools are loosely mounted, said shafts being capable of independent

endwise movement and being provided each with a cam device, a spring mounted mutilated gear coöoperative with said pinions, each of said cam devices being adapted to throw said gear out of operative position, tooth devices adapted when one of said cam devices is in operation to connect the associate spool with its shaft so that said spool will turn when said shaft is turned, and 10 hand devices for turning said shafts.

13. In ribbon mechanism for typewriting machines, the combination with a pair of ribbon spools, pinions constantly connected therewith, a mutilated driving gear which, 15 during each of its rotations, intermeshes in alternation with said pinions, a driving shaft operative on said gear, and pawl and ratchet mechanism for turning said driving shaft.

14. In a typewriting machine, the combination of a carriage, a rotary platen thereon, a sleeve supported on said platen, ribbon spools supported by said sleeve, spool turning mechanism mounted on said sleeve, and 20 a ribbon guide on said sleeve for guiding the ribbon from said spools over the printing point.

15. In a typewriting machine, the combination of a carriage, a rotary platen thereon, a sleeve supported on said platen, coaxial ribbon spools supported by said sleeve, spool turning mechanism mounted on said sleeve, and a ribbon guide on said sleeve for guiding the ribbon from said spools over the 25 printing point, said guide being hinged and provided with turning bars for directing the printing portion of the ribbon lengthwise of the printing line.

16. In a typewriting machine, the combi-

nation of a carriage, a rotary platen thereon, 40 a sleeve supported on said platen, ribbon spools supported by said sleeve, spool turning mechanism mounted on said sleeve, a ribbon guide on said sleeve for guiding the ribbon over the printing point, and a platen supported from said sleeve and over which said ribbon is fed.

17. In a typewriting machine, the combination of a platen, paper releasing devices controlled by a release key, and ribbon mechanism comprising devices for reversing the direction of feed of the ribbon, said reversing devices being operative by said release key.

18. In a typewriting machine, the combination of a platen, feed rolls coöoperative therewith, a release key for said feed rolls, a carriage carried ribbon, and means for reversing the feed of said ribbon operative from said key.

19. In a typewriting machine, the combination of a carriage, a platen thereon, feed rolls coöoperative therewith, a release key for said feed rolls, a main ribbon, a supplementary platen, a carriage carried ribbon coöoperative with the paper fed over said supplementary platen, and means operative by said release key for reversing the direction of feed of said supplementary ribbon.

In testimony whereof I have signed my name to this specification in the presence of two subscribing witnesses, this 4th day of April 1914.

WILLIAM GARFIELD SHELDON.
